(57) **CLAIM**

The ornamental design for a bottle stopper, as shown and described.

DESCRIPTION

FIG. 1 is an isometric view of a first embodiment of the claimed design from the top and a side thereof;

FIG. 2 is an isometric view of the first embodiment of the claimed design of FIG. 1 from the bottom and a side thereof; FIG. 3 is side view of the first embodiment of the claimed design of FIGS. 1 and 2, the side view being identical from all sides of the first embodiment of the claimed design;

FIG. 4 is a top plan view of the first embodiment of the claimed design of FIGS. 1-3;

FIG. 5 is a bottom plan view of the first embodiment of the claimed design of FIGS. 1-4;

FIG. 6 is an isometric view of a second embodiment of the claimed design from the top and a side thereof;

FIG. 7 is an isometric view of the second embodiment of the claimed design of FIG. 6 from the bottom and a side thereof; FIG. 8 is side view of the second embodiment of the claimed design of FIGS. 6 and 7, the side view being identical from all sides of the second embodiment of the claimed design;

FIG. 9 is a top plan view of the second embodiment of the claimed design of FIGS. 6-8;

FIG. 10 is a bottom plan view of the second embodiment of the claimed design of FIGS. 6-9;

FIG. 11 is an isometric view of a third embodiment of the claimed design from the top and a side thereof;

FIG. 12 is an isometric view of the third embodiment of the claimed design of FIG. 11 from the bottom and a side thereof; FIG. 13 is side view of the third embodiment of the claimed design of FIGS. 11 and 12, the side view being identical from all sides of the third embodiment of the claimed design;

FIG. 14 is a top plan view of the third embodiment of the claimed design of FIGS. 11-13;

FIG. 15 is a bottom plan view of the third embodiment of the claimed design of FIGS. 11-14;

FIG. 16 is an isometric view of a fourth embodiment of the claimed design from the top and a side thereof;

FIG. 17 is an isometric view of the fourth embodiment of the claimed design of FIG. 16 from the bottom and a side thereof; FIG. 18 is side view of the fourth embodiment of the claimed design of FIGS. 16 and 17, the side view being identical from all sides of the fourth embodiment of the claimed design;

FIG. 19 is a top plan view of the fourth embodiment of the claimed design of FIGS. 16-18; and,

FIG. 20 is a bottom plan view of the fourth embodiment of the claimed design of FIGS. 16-19.
